(57) **CLAIM**

The ornamental design for a sleeve for use with magnetic palette, as shown and described.

DESCRIPTION

FIG. 1 is a perspective view of a sleeve for use with magnetic palette.

FIG. 2 is a right elevational view of the sleeve of FIG. 1.

FIG. 3 is a left elevational view of the sleeve of FIG. 1.

FIG. 4 is a front elevational view of the sleeve of FIG. 1.

FIG. 5 is a rear elevational view of the sleeve of FIG. 1.

FIG. 6 is a top plan view thereof; and,

FIG. 7 is a bottom plan view thereof.

In all figures, broken lines illustrate environmental structures and form no part of the claimed design.

1 Claim, 4 Drawing Sheets
